(57) **CLAIM**

The ornamental design for a handle for a cannula, as shown and described.

DESCRIPTION

1. Handle for a cannula

1.0 shows the handle for a cannula in side or top view. Handle for a cannula comprising a rotational body, in particular a hyperboloid, for holding and a protrusion as a pick-up for the cannula; the hyperboloid includes ring-shaped protrusions; the cannula is shown in dotted lines (meaning that it is not part of the design); figure 1 shows the handle with indicated cannula in side or top view.
